CLAIM

The ornamental design for a robot teaching device, as shown and described.

DESCRIPTION

FIG. 1 is a front perspective view of a robot teaching device of the present disclosure;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is an enlarged view of the encircled portion identified as 9 in FIG. 1;

The evenly spaced broken lines shown in the drawings depict portions of the robot teaching device that form no part of the claimed design. The dot-dash-dot broken lines shown with in FIGS. 1 and 9 depict boundaries of the detailed enlargements that form no part of the claimed design.

1 Claim, 9 Drawing Sheets(56)
